UNITED STATES PATENT OFFICE

ZYGMUNT KUCZABOWSKI, OF ST. PAUL, MINNESOTA.

DESIGN FOR A WATCH-HOLDER.

49,357.

Specification for Design.

Patented July 11, 1916.

Application filed May 27, 1916. Serial No. 100,398. Term of patent 7 years.

To all whom it may concern:

Be it known that I, ZYGMUNT KUCZABOWSKI, a subject of the Czar of Russia, residing at St. Paul, in the county of Ramsey and State of Minnesota, have invented a new, original, and ornamental Design for a Watch-Holder, of which the following is a specification, reference being had to the accompanying drawing, forming part thereof.

Figure 1 is a front elevation of the device, and, Fig. 2 is a side elevation thereof.

I claim:

The ornamental design for a watch holder, as shown.

ZYGMUNT KUCZABOWSKI.

Witnesses:

MARTIN H. ALBIN,
BOLESLAW TAGZCZAK.
